CLAIM

The ornamental design for a multiple compartment trash container, as shown and described.

DESCRIPTION

FIG. 1 is a top, front side perspective view of a multiple compartment trash container showing my new design;

FIG. 2 is a front elevational view thereof;

FIG. 3 is a rear elevational view thereof;

FIG. 4 is a side elevational view thereof, the opposite side view being a mirror image of that shown;

FIG. 5 is a top plan view thereof; and

FIG. 6 is a bottom plan view thereof.

FIG.1

FIG. 2

FIG. 3

FIG. 4

FIG. 5

FIG. 6
